UNITED STATES PATENT OFFICE

123,810

DESIGN FOR A TOY TRAILER

Stanley Howard Levering, Clarks Summit, Pa.

Application June 13, 1940, Serial No. 92,978

Term of patent 3½ years

To all whom it may concern:

Be it known that I, Stanley Howard Levering, a citizen of the United States, residing at 212 Stone Avenue, Clarks Summit, Lackawanna County, Pennsylvania, have invented a new, original, and ornamental Design for a Toy Trailer, of which the following is a specification, reference being had to the accompanying drawing, forming part thereof.

Fig. 1 is a side elevational view of a toy trailer showing my new design.

Fig. 2 is a front elevational view thereof; and Fig. 3 is a rear elevational view.

I claim:

The ornamental design for a toy trailer, as shown.

STANLEY HOWARD LEVERING.
